IMAGE FORMING APPARATUS

CROSS-REFERENCE TO RELATED APPLICATIONS

This application relates to and claims priority rights from Japanese Patent Application No. 2019-155079, filed on Aug. 27, 2019, the entire disclosures of which are hereby incorporated by reference herein.

BACKGROUND

1. Field of the Present Disclosure

The present disclosure relates to an image forming apparatus.

2. Description of the Related Art

An inkjet-type image forming apparatus performs on-sheet preliminary ink ejection in order to restrain a trouble such as precision deterioration of an ink droplet hitting position and/or ink density deterioration with regard to a nozzle that ejects no ink during predetermined time. The on-sheet preliminary ink ejection is preliminary ink ejection performed (a) when an image specified by a user is printed and (b) on a paper sheet on which the image is printed.

Meanwhile, in case of commercial printing, for example, other than a user image, a post processing object may be printed such as a trim mark that specifies a cutting position for a cutting process or a color patch for evaluation of color reproducibility. In such a case, when the aforementioned on-sheet preliminary ink ejection is performed, if the ink droplet is ejected on the post processing object, then the postprocessing object on a printed matter is deteriorated and therefore a postprocess (cutting with a trim mark, color reproducibility evaluation using a color patch or the like) may be performed in low precision.

SUMMARY

An image forming apparatus according to an aspect of the present disclosure includes a print engine and a control unit. The print engine is configured to eject an ink droplet from a nozzle and thereby print an image to be printed on a print sheet. The control unit is configured to control the print engine. When performing on-sheet preliminary ink ejection, the control unit (a) determines a nozzle that performs the on-sheet preliminary ink ejection, (b) randomly selects on the print sheet an ejection position candidate of an ink droplet ejected from the determined nozzle, (c) determines whether the selected ejection position candidate is included by a mask area that includes a postprocessing object, (d1) if the selected ejection position candidate is not included by the mask area, sets as the selected ejection position candidate an ejection position of an ink droplet ejected from the determined nozzle, and (d2) if the selected ejection position candidate is included by the mask area, does not set as the selected ejection position candidate an ejection position of an ink droplet ejected from the determined nozzle and sets an ejection position of an ink droplet ejected from the determined nozzle outside of the mask area.

These and other objects, features and advantages of the present disclosure will become more apparent upon reading of the following detailed description along with the accompanied drawings.

2

BRIEF DESCRIPTION OF THE DRAWINGS

FIG. 1 shows a side view that indicates an internal mechanical configuration of an image forming apparatus in an embodiment according to the present disclosure;

FIG. 2 shows a plane view of the image forming apparatus shown in FIG. 1;

FIG. 3 shows a block diagram that indicates an electronic configuration of the image forming apparatus 10 in the 10 embodiment according to the present disclosure;

FIG. 4 shows a diagram that explains an example of a postprocessing object and a mask image used in the image forming apparatus 10 shown in FIG. 1;

FIG. 5 shows a diagram that explains an example of 15 circumvention control in the image forming apparatus 10 shown in FIG. 1; and

FIG. 6 shows a diagram that explains three control types of the circumvention control in the image forming apparatus 10 shown in FIG. 1.

DETAILED DESCRIPTION

Hereinafter, an embodiment according to an aspect of the present disclosure will be explained with reference to drawings.

FIG. 1 shows a side view that indicates an internal mechanical configuration of an image forming apparatus in an embodiment according to the present disclosure. FIG. 2 shows a plane view of the image forming apparatus shown in FIG. 1.

The image forming apparatus 10 in this embodiment is an apparatus such as printer, copier, facsimile machine or multi function peripheral, and includes an inkjet color printing mechanism of a line head type in this embodiment.

The image forming apparatus 10 includes a print engine 10a and a sheet transportation unit 10b. The print engine 10a ejects an ink droplet from a nozzle and thereby physically prints an image to be printed on a print sheet (print paper sheet or the like). The sheet transportation unit 10b transports the print sheet to the print engine 10a.

In this embodiment, the print engine 10a includes line-head-type inkjet recording units 1a to 1d corresponding to four ink colors: Cyan, Magenta, Yellow, and Black.

As shown in FIG. 2, in this embodiment, each inkjet recording unit 1a, 1b, 1c or 1d includes plural (here, three) head units 11. The head units 11 are arranged along a primary scanning direction, and are capable of being mounted to and demounted from a main body of the image forming apparatus. Each inkjet recording unit 1a, 1b, 1c or 1d may include only one head unit 11.

Further, in this embodiment, the sheet transportation unit 10b includes (a) a circular-type transportation belt 2, arranged so as to face the print engine 10a, that transports a print sheet, (c) a driving roller 3 and a driven roller 4 around which the transportation belt 2 is hitched, (d) a nipping roller 5 that nips the print sheet with the transportation belt 2, and (e) an output roller pair 6.

The driving roller 3 and the driven roller 4 rotate the transportation belt 2. The nipping roller 5 nips an incoming print sheet transported from a sheet feeding cassette 20-1 or 20-2 mentioned below, and the nipped print sheet is transported by the transportation belt 2 to printing positions of the inkjet recording units 1a to 1d in turn, and on the print sheet, images of respective colors are printed by the inkjet recording units 1a to 1d. Subsequently, after the printing, the print sheet is outputted by the output roller pair 6 to an output tray 10c or the like.

Further, the sheet transportation unit **10b** includes plural sheet feeding cassettes **20-1** and **20-2**. The sheet feeding cassettes **20-1** and **20-2** store print sheets **101** and **102**, and push up the print sheets **101** and **102** using lift plates **21** and **24** so as to cause the print sheets **101** and **102** to contact with pickup rollers **22** and **25**, respectively. The print sheets **101** and **102** put on the sheet feeding cassettes **20-1** and **20-2** are picked up to sheet feeding rollers **23** and **26** by the pickup rollers **22** and **25** sheet by sheet from the upper side, respectively. The sheet feeding rollers **23** and **26** are rollers that transport the print sheets **101** and **102** sheet by sheet fed by the pickup rollers **22** and **25** from the sheet feeding cassettes **20-1** and **20-2** onto a transportation path.

A transportation roller **27** is a transportation roller on the transportation path common to the print sheets **101** and **102** transported from the sheet feeding cassettes **20-1** and **20-2**. The registration roller **28** temporarily stops the incoming print sheet **101** or **102** in transportation, and transports this print sheet **101** or **102** to the print engine **10a** at a secondary sheet feeding timing. The secondary sheet feeding timing is instructed by a control unit **81** mentioned below such that an image is formed at a specified position on the print sheet **101** or **102**.

For example, the sheet feeding cassettes **20-1** and **20-2** store print sheets of different types from each other.

FIG. 3 shows a block diagram that indicates an electronic configuration of the image forming apparatus **10** in the embodiment according to the present disclosure. As shown in FIG. 3, the image forming apparatus **10** includes not only an image outputting unit **71** that includes the mechanical configuration shown in FIGS. 1 and 2 but an operation panel **72**, a processor **73**, a communication device **74**, and a processor **75**.

The operation panel **72** is arranged on a housing surface of the image forming apparatus **10**, and includes a display device such as a liquid crystal display and an input device such as a hard key and/or touch panel, and displays sorts of messages for a user using the display device and receives a user operation using the input device.

The storage device **73** is a non-volatile storage device (flash memory, hard disk drive or the like) in which data, a program and the like have been stored and are required for control of the image forming apparatus **10**. In the storage device **73**, preliminary ink ejection setting data **73a** has been stored. The preliminary ink ejection setting data **73a** indicates a control type of preliminary ink ejection, and this control type is set by a user.

The communication device **74** is a device that performs data communication with a host apparatus **41**, and receives a print request or the like from the host apparatus **41**. For example, the communication device **74** is a peripheral device interface, a network interface or the like.

The processor **75** includes a computer that acts in accordance with a program, an ASIC (Application Specific Integrated Circuit) that performs a predetermined action, and/or the like, and acts as sorts of processing units using the computer, the ASIC and/or the like. This computer includes a CPU (Central Processing Unit), a ROM (Read Only Memory), a RAM (Random Access Memory) and the like, and loads a program stored in the storage device **73**, the ROM or the like to the RAM and executes the program using the CPU and thereby acts as processing units (with the ASIC if required).

Here the processor **75** acts as a control unit **81** and an image processing unit **82**.

The control unit **81** controls the image outputting unit (the print engine **10a**, the sheet transportation unit **10b** and the

like), and thereby performs a print job requested through the aforementioned print request by a user. In this embodiment, the control unit **81** causes the image processing unit **82** to perform a predetermined image process, and controls the head units **11** and causes the head units **11** to eject ink and thereby forms a printing image on a print sheet. The image processing unit **82** performs a predetermined image process such as RIP (Raster Image Processing), color conversion, halftoning and/or the like for image data of a printing image.

In particular, the control unit **81** performs on-sheet preliminary ink ejection as preliminary ink ejection of the print engine **10a**, if necessary.

It should be noted that “preliminary ink ejection” is an action that ejects ink for a maintenance purpose rather than for an image forming purpose with a nozzle of the head units **11** that has not been used during a predetermined time or for predetermined printed pages. Further, “on-sheet preliminary ink ejection” is preliminary ink ejection performed onto a user image sheet.

Specifically, when performing on-sheet preliminary ink ejection of the print engine **10a**, the control unit **81** (a) determines a nozzle that performs the on-sheet preliminary ink ejection, (b) randomly selects on the print sheet an ejection position candidate of an ink droplet ejected from the determined nozzle, (c) determines whether or not the selected ejection position candidate is included by a mask area that includes a postprocessing object, (d1) if the selected ejection position candidate is not included by the mask area, sets as the selected ejection position candidate an ejection position of an ink droplet ejected from the determined nozzle, and (d2) if the selected ejection position candidate is included by the mask area, does not set as the selected ejection position candidate an ejection position of an ink droplet ejected from the determined nozzle outside of the mask area.

The ejection position candidate of an ink droplet ejected by the determined nozzle is set as a position away from another ejection position candidate by a predetermined distance or longer (i.e. by the predetermined number of pixels or more) such that ejection position candidates are dispersed on the print sheet.

Here, the postprocessing object is a trim mark or a color patch, and there may be plural postprocessing objects that are trim marks, color patches, or a combination of them. Further, the mask area includes (a) such a postprocessing object and (b) a margin set with a predetermined width (here, a width equal to or wider than a maximum width of the ink droplet) on an outer edge of the postprocessing object. This width of the margin may be enabled to be set by a user (for example, by a user operation to the operation panel **72**).

The postprocessing object is printed at a fixed position on the print sheet, and the mask area is specified by a mask image (an image with an identical size to the print image and, for example, with pixel values set as 1 in the mask area and set as 0 outside of the mask area) stored in the storage device **73**; and the control unit **81** refers to the mask image and thereby determines whether or not the selected ejection position candidate (i.e. a pixel position of it) is included by the mask area that includes the postprocessing object.

FIG. 4 shows a diagram that explains an example of a postprocessing object and a mask image used in the image forming apparatus **10** shown in FIG. 1. For example, as shown in FIG. 4, a mask area **113** is set for a trim mark **111** and a color patch **112** included by the print image **101**. The mask area **113** is expressed as an area **121** that has a specific

pixel value in a mask image 102. The mask area 113, that is, the mask image 102 may be editable.

Further, in this embodiment, the control unit 81 performs circumvention control that causes an ejection position of an ink droplet in the on-sheet preliminary ink ejection to circumvent the postprocessing object. In the circumvention control, the control unit 81 selects one of predetermined three control types in accordance with user setting in the preliminary ink ejection setting data 73a, and if the selected ejection position candidate is included by the mask area, the control unit 81 performs on-sheet preliminary ink ejection of the determined nozzle in accordance with the selected control type.

FIG. 5 shows a diagram that explains an example (the control type B mentioned below) of circumvention control in the image forming apparatus 10 shown in FIG. 1. FIG. 6 shows a diagram that explains three control types of the circumvention control in the image forming apparatus 10 shown in FIG. 1. Here, as shown in FIG. 6, for example, a first control type (the control type A) among the three control types indicates a control manner that makes ejection timing of an ink droplet ejected from the determined nozzle earlier and thereby sets an ejection position of the ink droplet ejected from the determined nozzle outside of the mask area. Further, a second control type (the control type B) among the three control types indicates, as shown in FIG. 5, a control manner that delays ejection timing of an ink droplet ejected from the determined nozzle and thereby sets an ejection position of the ink droplet ejected from the determined nozzle outside of the mask area. Furthermore, a third control type (the control type C) among the three control types indicates a control manner that performs ejection of the ink droplet ejected from the determined nozzle on a subsequent print sheet to the print sheet on which the mask area is set.

Thus, in the control type A or B, the ejection timing of the ink droplet is shifted and thereby the ejection position of the ink droplet is shifted along the transportation direction (i.e. the secondary scanning direction) so as to get outside of the mask area. In the control type C, the control unit 81 memorizes in the RAM or the like a nozzle number of a nozzle that does not perform the preliminary ink ejection on a current print sheet, and in the printing of a subsequent print sheet, reads the nozzle number and performs the preliminary ink ejection of the nozzle specified by this nozzle number.

The following part explains a behavior of the image forming apparatus 10.

If the on-sheet preliminary ink ejection is performed, upon receiving a print request using the communication device 74, the control unit 81 firstly determines one or plural nozzles that should perform preliminary ink ejection on the basis of an unused period or the like, and randomly selects an ejection position candidate of an ink droplet ejected from each nozzle of the determined nozzle(s).

In this embodiment, the head unit 11 is fixed and the nozzle does not move but the print sheet moves in the transportation direction (i.e. the secondary scanning direction); and therefore, a position in the transportation direction (i.e. the secondary scanning direction) is randomly selected as the ejection position candidate. However, if the preliminary ejection for plural nozzles is performed on one print sheet, a position is selected as the ejection position candidate away from another ejection position candidate by a predetermined distance or longer (i.e. by the predetermined number of pixels or more).

Subsequently, the control unit 81 refers to the mask image based on the postprocessing object, and thereby determines

whether or not the ejection position candidate of each of the determined nozzle(s) is included by the mask area.

If the ejection position candidate of the target nozzle is not included by the mask area, then the control unit 81 sets an ejection position of the target nozzle as the ejection position candidate.

If the ejection position candidate of the target nozzle is included by the mask area, then the control unit sets an ejection position outside of the mask area, corresponding to the ejection position candidate of the target nozzle.

Here, for example, in case of the control type A, the ejection position is set as a position prior to the ejection position candidate along the secondary scanning direction and outside of the mask area (e.g. adjacent to an outer edge 15 of the mask area). Further, in case of the control type B, the ejection position is set as a position posterior to the ejection position candidate along the secondary scanning direction and outside of the mask area (e.g. adjacent to an outer edge 20 of the mask area). Furthermore, in case of the control type C, for example, the ejection position is set as the same position on the next page.

In the aforementioned manner, the ejection position of the target nozzle of the preliminary ink ejection is determined.

Meanwhile, the image processing unit 82 generates a print image 25 corresponding to the received print request.

Subsequently, the control unit 81 controls the image outputting unit 71 and thereby prints the print image on a print sheet and performs the preliminary ink ejection at the determined ejection position (at the determined ejection timing) as mentioned, for the target nozzle of the preliminary ink ejection.

As mentioned, in the aforementioned embodiment, the print engine 10a ejects an ink droplet from a nozzle and thereby prints an image to be printed on a print sheet. When 35 performing on-sheet preliminary ink ejection of the print engine 10a, the control unit 81 (a) determines a nozzle that performs the on-sheet preliminary ink ejection, (b) randomly selects on the print sheet an ejection position candidate of an ink droplet ejected from the determined nozzle, (c) determines whether the selected ejection position candidate is included by a mask area that includes a postprocessing 40 object, (d1) if the selected ejection position candidate is not included by the mask area, sets as the selected ejection position candidate an ejection position of an ink droplet ejected from the determined nozzle, and (d2) if the selected ejection position candidate is included by the mask area, does not set as the selected ejection position candidate an ejection position of an ink droplet ejected from the determined nozzle and sets an ejection position of an ink droplet ejected from the determined nozzle outside of the mask area.

Consequently, the on-sheet preliminary ink ejection does not result in the deterioration of the postprocessing object, and therefore, precision decrease is restrained of a postprocess using the postprocessing object.

It should be understood that various changes and modifications to the embodiments described herein will be apparent to those skilled in the art. Such changes and modifications may be made without departing from the spirit and scope of the present subject matter and without diminishing its intended advantages. It is therefore intended that such changes and modifications be covered by the appended claims.

What is claimed is:

1. An image forming apparatus, comprising:
a print engine configured to eject an ink droplet from a nozzle and thereby print an image to be printed on a print sheet; and

a control unit configured to control the print engine; wherein when performing on-sheet preliminary ink ejection, the control unit (a) determines a nozzle that performs the on-sheet preliminary ink ejection, (b) randomly selects on the print sheet an ejection position candidate of an ink droplet ejected from the determined nozzle, (c) determines whether the selected ejection position candidate is included by a mask area that includes a postprocessing object, (d1) if the selected ejection position candidate is not included by the mask area, sets as the selected ejection position candidate an ejection position of an ink droplet ejected from the determined nozzle, and (d2) if the selected ejection position candidate is included by the mask area, does not set as the selected ejection position candidate an ejection position of an ink droplet ejected from the determined nozzle and sets an ejection position of an ink droplet ejected from the determined nozzle outside of the mask area.

2. The image forming apparatus according to claim 1, wherein the postprocessing object is either a trim mark or a color patch.

3. The image forming apparatus according to claim 1, wherein if the selected ejection position candidate is included by the mask area, the control unit makes ejection timing of the ink droplet ejected from the determined nozzle earlier and thereby sets the ejection position of the ink droplet ejected from the determined nozzle outside of the mask area.

4. The image forming apparatus according to claim 1, wherein if the selected ejection position candidate is included by the mask area, the control unit delays ejection timing of the ink droplet ejected from the determined nozzle and thereby sets the ejection position of the ink droplet ejected from the determined nozzle outside of the mask area.

5. The image forming apparatus according to claim 1, wherein if the selected ejection position candidate is included by the mask area, the control unit performs ejection of the ink droplet ejected from the determined nozzle on a subsequent print sheet to the print sheet on which the mask area is set.

6. The image forming apparatus according to claim 1, wherein

the control unit selects a control type from a predetermined three control types in accordance with user setting, and if the selected ejection position candidate is included by the mask area, performs the on-sheet preliminary ink ejection of the determined nozzle in accordance with the selected control type;

a first control type among the three control types makes ejection timing of the ink droplet ejected from the determined nozzle earlier and thereby sets the ejection position of the ink droplet ejected from the determined nozzle outside of the mask area;

a second control type among the three control types delays ejection timing of the ink droplet ejected from the determined nozzle and thereby sets the ejection position of the ink droplet ejected from the determined nozzle outside of the mask area; and

a third control type among the three control types performs ejection of the ink droplet ejected from the determined nozzle on a subsequent print sheet to the print sheet on which the mask area is set.

7. The image forming apparatus according to claim 1, wherein

the mask area includes (a) the postprocessing object and (b) a margin set with a predetermined width on an outer edge of the postprocessing object; and

the width of the margin is enabled to be set by a user.
